UNITED STATES PATENT OFFICE

PAUL F. LONDON, OF ST. LOUIS, MISSOURI

TELEPHONE ATTACHMENT

Application filed October 18, 1929. Serial No. 400,477.

This invention relates to telephone attachments, and has special reference to a device of novel construction for attachment to a telephone instrument so as to operate automatically and as an incident to the removal of the receiver from the hook, or other support, with which the instrument is provided to illuminate the telephone dial or any other part brought in position for illumination by 10 the illuminating device.

An object of the invention is to provide a device having novel means for attachment to the telephone instrument, and novel means under control of a movable part of the telephone instrument so as to operate automatically and as an incident to removal of the receiver for use to illuminate the dial or other desired part of the instrument.

Another object of the invention is to provide an improved illuminating attachment with improved means for attaching the same to a telephone instrument and embodying an improved device for controlling the instrument as to operate the illuminating element 25 thereof automatically and as an incident to removal of the telephone receiver, substantially in the manner herein disclosed, reference being made to the accompanying drawings, in which

Fig. 1 is a front elevation of the telephone instrument of familiar construction having my improved attachment in connection therewith.

Fig. 2 is a side elevation of the instrument 35 showing the attachment in connection therewith.

Fig. 3 is a side elevation of the attachment removed from the telephone instrument, parts being shown in section.

Fig. 4 is an enlarged sectional view showing some of the important features of the invention.

The device shown in the drawings comprises a casing 1 which encloses a battery 2 which constitutes a source of electrical energy for operating a lamp 3. One side of the battery 2 is in circuit with a spring 4 supported and enclosed within a cup 5 of insulating material mounted in the lower end of 50 the casing 1. An electric circuit wire 6 is en-

closed within insulation 7 and leads to connection with the spring 4. The insulated wire 6 extends upwardly within the casing 1 and between the wall of the casing and the battery 2 and outwardly from the casing 55 through a hole 8.

A metallic clamp 9, comprising an arcuate resilient plate, has one edge attached to the casing 1. This plate is curved and shaped so as to clamp around the stand or post 10 of a telephone instrument and illustrates one form of a device for attaching the present invention to a telephone instrument of the type shown. Of course, the form of support for attaching the device to a telephone instrument will be varied to meet the needs of each form of instrument, and the invention is not restricted to this specific type, except as defined by the claim pertaining thereto. It is clear from the drawings that the clamp 9 will engage around the upper end of a telephone member 10 and support the device in position to cooperate with the telephone instrument to obtain the desired results. An advantage of this type of clamp 9 for use in connection with the telephone instrument shown is that the device may be readily attached to and removed from the instrument without marring or removing any of the parts of either the telephone instrument or the present invention. Another advantage is that the device may be readily adjusted along the telephone instrument to proper position for cooperation with the parts thereof. Still another advantage is that the device may be attached to a telephone instrument as an accessory or a supplemental equipment and it is not required to be built or embodied in the telephone instrument when the instrument is manufactured. These and other advantages 80 are obtained by this invention.

The insulated wire 6, after leaving the hole 8 of the casing 1, is enclosed and confined in a rolled portion 11 at the upper end of the clamp 9. The clamp 9 has rigid or integral 95 therewith an extended curved arm 12, the upper edge of which also has a rolled portion 13 enclosing the insulated wire which extends through a socket 14 on the end of the arm 12 in which the lamp 3 is removably secured. 100

Thus, the filament of the lamp 3, is as familiar, is in circuit with the wire 6 so that when the circuit is closed the lamp will be operated, with the result that the telephone dial 15, or any other part, will be illuminated.

5 The lamp 3 is covered by a reflector or canopy 16 which reflects the rays of light downwardly or in any desired direction and to any desired place.

10 The casing 1 is a metallic casing and is equipped with a removable lid or cover 17. The cover 17 has a depending annular flange 18 designed and arranged to telescope upon the upper end of the casing 1, and said flange 15 is provided at appropriate points and intervals with sockets 19 arranged to engage with beads 20 formed in the wall of the casing 1 for this purpose.

15 A resilient circuit closing device comprising a resilient arm 21 has one end of said arm 21 removably attached to a removable screw 22. The screw 22 passes through and is supported by an insulation sleeve 23 mounted in a hole in the lid 17. A nut 24 is screwed onto the lower end of the screw 22 and clamps the end of the arm 21 against the insulation 23 which is thereby supported out of circuit with the casing. The inner lower end of the screw 22 contacts with a battery terminal 30 25 (Fig. 4).

20 The arm 21 projects through a hole 26 in the wall 18 of the lid 17 and has a downwardly extended portion 27 terminating in a lateral extension 28. The lateral extension 25 28 is covered by insulating material 29.

25 A screw 30 is screwed into a socket 31 in the lid 17 and has on its lower end a piece of insulating material 32.

30 The natural and inherent power and resiliency of the arm 21 is sufficient to raise said arm into contact with the upper edge of the hole 26 and thus ground the circuit from the battery, thereby closing the circuit and operating the lamp 3. However, the screw 30 35 may be operated downwardly a sufficient distance to place the insulating piece 32 in position to act as an abutment to limit extent of upward movement of the arm 21 and prevent said arm from contacting with the lid 17 at 40 the upper side of the hole 26. Thus, the screw 30 is adjustable to prevent closing of the circuit.

35 When this device is attached to the telephone instrument substantially in the manner shown, it is adjusted along the post or stand 10 to a position in which the end of the arm 28, having the insulating substance 29 thereon, is under and engaged by the receiver hook 33. The weight of the receiver 40 34 on the hook 33, as is well known, is sufficient to hold the hook 33 in its downward position. When the receiver hook 33 is in its downward position, it holds the arm 21 bent downwardly so that said arm 21 is wholly out 45 of contact with the flange 18 of the lid 17.

Thus, the arm 21 is out of circuit with the casing 1 and the circuit is open, so that the lamp 3 remains unoperated. When the receiver 34 is removed from the hook 33, said hook 33, as is well known, rises leaving the arm 21 70 free to be raised by the inherent resiliency thereof to a position in which said arm 21 contacts with the lid 17—18 at the upper edge of the hole 26, thus automatically closing the circuit and operating the lamp 3.

75 The power by which the clamp 9 is engaged with the post 10 is sufficient to support the device in the position described, so that the device will operate as desired. The clamp 9 is of such construction that the device of the present invention may be readily turned about or moved along the post 10 to proper adjustment, so that the receiver hook 33 will cooperate with the device.

80 It is now clear that this invention obtains all of the objects, purposes and advantages herein mentioned, or otherwise apparent to those skilled in the art. The construction, arrangement and relationship of the parts may be varied within the scope of equivalents 85 without departure from the nature and principle of the invention. And, the structure may also be varied so as to adapt it for attachment to telephone instruments of other types, such variations will be readily apparent to 90 those skilled in the art without specific illustration.

95 I claim:

A device of the character described comprising a support, a source of electrical energy, a lamp carried by said support in circuit with one side of said source of electrical energy and the support, a case carried by said support and forming a housing for said source of electrical energy, a cover for said case in circuit with the other side of said source of electrical energy, having an aperture in one side thereof, a switch arm carried by said cover and insulated therefrom projecting through but clear of said aperture, the free end of said switch being positioned below the receiver hook whereby said switch is permitted to contact with the wall of said aperture when the hook is raised, and a manually operable member carried by said cover to maintain said switch in an open position.
